UNITED STATES PATENT OFFICE.

WILLIAM C. SKINNER, OF TOLEDO, OHIO.

DESIGN FOR A RANGE AND KITCHEN-CABINET.

SPECIFICATION forming part of Design No. 31,557, dated September 26, 1899.

Application filed August 26, 1899. Serial No. 728,627. Term of patent 14 years.

To all whom it may concern:

Be it known that I, WILLIAM C. SKINNER, a citizen of the United States, residing in the city of Toledo, county of Lucas, and State of Ohio, have invented and produced a new and original Design for a Range and Kitchen-Cabinet, of which the following is a specification, reference being had to the accompanying drawing, forming a part thereof.

10 The single figure of the drawing presents a perspective elevation of my new design.

As therein shown, the leading and distinguishing feature or characteristic of the design is found not so much in any special feature or part as in the appearance of the design as a whole and in which is seen a double cabinet partially divided and peculiarly embellished in its middle portion. This appearance when analyzed reveals the fronts 2 and tops 3 15 of a rather plain cabinet, and between these

is a deep transverse recess 4, over which there extends a more or less complete covering 5, resembling in part the appearance of grids for gas-burners. The two top surfaces 3 are perfectly plain and smooth and the fronts 2 are likewise comparatively plain, but have such relief as becomes unpretentious cabinets having drawers, which show on their faces, and in this instance flat projecting surfaces 7 and 8 here and there. 30

What I claim is—

The design for a range and kitchen-cabinet, substantially as shown and described.

Witness my hand to the foregoing specification this 23d day of August, 1899.

WILLIAM C. SKINNER.

Witnesses:

H. T. FISHER,

R. B. MOSER.
